CLAIM

I claim the ornamental design for an outsole, as shown and described.

DESCRIPTION

FIG. 1 is a bottom plan view of an outsole showing my new design, the broken lines showing a shoe upper throughout the views being understood to represent a portion of the design that forms no part of the claim;

FIG. 2 is a left view of the outsole in accordance with the embodiment of the new design shown in FIG. 1;

FIG. 3 is a right view of the outsole in accordance with the embodiment of the new design shown in FIG. 1;

FIG. 4 is a front view of the outsole in accordance with the embodiment of the new design shown in FIG. 1;

FIG. 5 is a back view of the outsole in accordance with the embodiment of the new design shown in FIG. 1; and,

FIG. 6 is a bottom perspective view of the outsole in accordance with the embodiment of the new design shown in FIG. 1.
